UNITED STATES PATENT OFFICE

2,609,720

DIE FOR PIPE TONGS AND METHOD
OF MAKING SAMENorval J. Barnard, Oklahoma City, Okla., as-
signor, by mesne assignments, to Charles C.
Weiss, Oklahoma City, Okla.

Application October 19, 1951, Serial No. 252,173

8 Claims. (Cl. 81—186)

1

This invention relates to jaw face inserts, commonly known in well drilling parlance as dies, for use in various gripping devices such as tongs for gripping drill pipe and preventing slipping of the pipe when unthreading or breaking out drill pipe joints incidental to rotary drilling practices. Dies of this character comprise toothed metal bars that are retained in groove-like seats within the gripping device and to effect proper grip of such dies, the teeth must be sufficiently hard to penetrate the surface of the drill pipe or object to be gripped thereby. The dies are applied and removed from their groove-like seats by driving them into and out of position with a hammer, with the blows being struck against an end of the die.

It is obvious that due to the hardness of the teeth the bars are very brittle so that small particles break off and fly away with considerable velocity when the dies are struck with the hammer. Such flying particles are extremely hazardous because they are apt to strike the eye or other vulnerable part of the wielder of the hammer or nearby persons.

Insurance companies have long experienced this hazard and teach the use of goggles when driving in the dies, but tool dressers seldom go to this trouble with the result that many injuries occur. The possibility of injury may be realized when it is considered that as many as a gross of dies may be used in the course of drilling a single well.

It is therefore the principal object of the invention to avoid this hazard by providing a die with a hard exterior surface and a relatively soft central core extending through the ends of the die to provide relatively soft unbreakable portions for receiving the impact of a hammer when the die is driven into and removed from its seat in the jaw of a tong head.

It is also an object of the invention to provide a simple and inexpensive method for forming the die to provide the hardened exterior surface and the soft interior core exposed at ends of the die.

In accomplishing these and other objects of the invention hereinafter pointed out, I have provided improved structure, the preferred form of which is illustrated in the accompanying drawing, wherein:

Fig. 1 is a perspective view of the jaw of a drill pipe tong and showing a die being driven into the groove-like seat of the jaw.

Fig. 2 is a plan view of the jaw showing the die in place and particularly illustrating the cross-sectional shape of the die seat and the close fit of the die therein.

2

Fig. 3 is a central longitudinal section through a die constructed in accordance with the present invention.

Fig. 4 is an enlarged perspective view of the die.

Figs. 5 to 8 are sections through one end of the die showing different steps involved in the construction thereof.

Referring more in detail to the drawings:

1 designates a jaw of a conventional tong head (not shown) which is used for gripping, for example, a drill pipe as when unthreading and breaking out drill pipe joints on pulling the drill pipe from a bore hole in the rotary drilling wells. In order to enhance gripping action of the jaws, the jaws are provided with a die 2 including a bar-like body 3 formed of metal and having tapered sides 4—5, a front gripping face 6 provided with a plurality of teeth 7, and a back face 8 that joins with the side edges 4 and 5 on acute angles as best shown in Fig. 6.

The die substantially corresponds in length with the depth of the jaw and is retained therein by means of a driving fit within a groove 9 having undercut sides 10 and 11 and a flat bottom face 12 joining therewith at angles corresponding with the angles between the back and side edges of the die.

The cross section of the die and its groove-like seat are therefore of substantially dovetail shape so that the side edges 4 and 5 of the die closely engage the corresponding sides 10 and 11 of the groove for wedging the back face 8 of the die against the bottom face 12.

As above mentioned, the dies are applied by inserting one end thereof within the upper open end of the groove 9 and driving the die into the groove by striking the opposite end with a hammer 13 as shown in Fig. 1. In order to effect indentation of the teeth within the surfaces of an object to be gripped by the die, for example, the drill pipe, the teeth of the die must have a relatively high degree of hardness.

Heretofore, such dies have such hardness extending through the metal and the ends thereof are so hard and brittle that hammer blows chip off particles which fly in various directions so that they are extremely hazardous to any person within the vicinity of the work.

In overcoming this hazard, I form the die of uniformly soft metal capable of being heat treated to a desired degree of hardness. Such metal is easily shaped and provided with the desired teeth before heat treatment as shown in Fig. 5. After the die is shaped, it is heat treated to form an exterior shell portion 14 as shown in Fig. 6 which has the required degree of hard-

ness and a core 15 sufficiently soft to provide the required toughness and strength for the die. When thus formed the hardened portion extends across the ends of the die as shown at 16 in Fig. 6. The ends are then removed as by grinding to expose ends 15' of the core 15 as shown in Fig. 7. The edges 17 at the ends of the die are beveled or otherwise formed as shown at 18 in Fig. 8 so that the core portion 15 is completely exposed and projects beyond the hardened areas at the surrounding side faces of the die so that when the die is driven into or out of position within the jaw of the die, the hammer contacts the relatively soft projecting ends of the core without danger of chipping off any particles that are hazardous to persons in the vicinity of the work.

In applying a die constructed as described, one end of the die is placed within the groove 9 and the blows of the hammer 13 are applied to the exposed ends of the relatively soft core 15 at the other end of the die to drive the die into its seat. Since the end surface of the die is spaced from the exterior hardened surface by the formation of the end edges, the hammer does not make contact with any hardened surface of the die. Therefore, the die may be safely driven into position or removed by means of a hammer.

What I claim and desire to secure by Letters Patent is:

1. A die of the character described including a bar-like body portion having a relatively hard toothed gripping face and a relatively soft core and substantially hard side surfaces surrounding the core with the ends of the core being exposed and projecting beyond the hardened side surfaces of the die.

2. A heat treated die of the character described including a metal body having a relatively soft core and exterior side portions surrounding the core and having a relatively higher degree of hardness than the core with the side portions terminating short of opposite ends of the die.

3. A die of the character described including a body portion having a face provided with a plurality of teeth, a substantially flat back face, and tapered side faces, all of said faces being relatively hard and surrounding a softer core with the ends of the core being exposed and projecting beyond the hardened side faces of the die.

4. A die of the character described including

a metal body having a relatively soft core and substantially hard side portions surrounding the core with an end of the core being exposed and projecting beyond the hardened side portions of the die, said projecting end of the core being beveled toward the hard side portions.

5. A die of the character described including a body portion having a face provided with a plurality of teeth, a substantially flat back face, and tapered side faces, all of said faces being relatively hard and surrounding a softer core with the ends of the core being exposed and projecting beyond the hardened side faces of the die, said ends of the core being beveled outwardly toward said hard faces.

6. The method of forming a die of the character described including shaping a bar of metal to the form of a die, hardening face portions of the die to provide relatively hard exterior faces, and removing the hardened portions from an end of the die to expose relatively soft metal at the end of the die.

7. The method of forming a die including shaping a bar of metal to form the die, forming teeth on one surface of the die, heat treating the die to provide relatively hard teeth and exterior surfaces, and grinding off ends of the die to expose relatively soft interior portions at the ends of the die.

8. The method of forming a die including shaping a bar of metal to form the general shape of the die, forming teeth on one surface of the die, heat treating the die to provide relatively hard exterior surfaces, removing the hard exterior surfaces from ends of the die to expose relatively soft interior portions at the ends of the die, and removing the edges of the hardened side portions of the die surrounding the exposed soft end portions.
